METHOD OF MAKING SLIP LASTED
WELT SHOES

Jack Meltzer, New York, N. Y.

Application March 25, 1948, Serial No. 17,092

1 Claim. (Cl. 12—142)

1 My present invention relates generally to shoes, and has particular reference to an improved construction of the slip-lasted variety and to a method of making it.

A general object of the invention is to provide an improved footwear construction, which is simple and inexpensive, which is suitable for the creation of a large variety of shoes, slippers, sandals and similar items intended for either street wear or for indoor use, which is adapted to form an article of unusually staunch yet comfortable wearing qualities, and which lends itself readily to the employment of various ornamental materials and to numerous variations in style.

A more particular object is to impart these qualities to an article of footwear which is of the well-known slip-lasted type in which there is a socklining of the stitched-in type, and to combine the advantages and low expense of the slip-lasting procedure and the slip-lasted product with the advantages of a pre-welted shoe.

The present improved shoe comprises an upper, a socklining, a welt strip carried by the upper, and an outer sole. The upper may consist of a single ply of material, or of two plies defining a downwardly-opening pocket between them adapted to accommodate a reinforcement. The welt strip may be stitched directly to the upper, or may be carried by the upper with the aid of an intermediate platform cover. The socklining is in neatly stitched engagement with the upper, and the outer sole is in stitched association with the welt strip.

A particular feature of the invention resides in the association of the parts in such a manner that the upper is provided with a lasting allowance or anchoring extension by means of which I am enabled not only to fit the upper more accurately and neatly to a last, but also to anchor the upper with unusual firmness and permanence to the under structure of the shoe.

In all embodiments of the invention, it is a characterizing feature to stitch the socklining to the upper along a line appreciably spaced from the lower edge of the upper. Where the upper is formed of separate inner and outer plies, the socklining is stitched only to the inner ply, thus affording the added advantage of allowing the insertion of a counter into sandwiched position between the two plies.

In one embodiment of the invention, the welt strip is stitched directly to the upper, or to the outer ply of the upper where a two-ply is used. In a modified construction, the welt strip is

2 carried by the upper through the medium of a platform cover.

The present procedure is simple, efficient, inexpensive, and requires no special skill on the part of the operator. The resultant article of footwear is unusually comfortable, attractive in appearance, and capable of withstanding long usage.

Several ways of achieving the foregoing general objects and advantages, and such other objects and advantages as may hereinafter appear or be pointed out, are illustratively exemplified in the accompanying drawings, in which:

Fig. 1 is a perspective view of a shoe constructed in accordance with the present invention;

Fig. 2 is an exaggerated cross-sectional view taken substantially along the line 2—2 of Fig. 1;

Figs. 3 and 4 are views similar to Fig. 2, illustrating modifications; and

Fig. 5 is a perspective view of an illustrative reinforcement.

The improved procedure can be readily explained by reference to Fig. 2. As a first step, an upper 10, a socklining 11, and a welt strip 12 are stitched together as at 13. The socklining 11 is arranged with its top surface lying next to the inner surface of the upper 10. The welt strip 12 is arranged with its top surface lying next to the outer surface of the upper 10. While I have shown one set of stitches 13, simultaneously connecting both the socklining 11 and the welt strip 12 to the upper 10, it will be understood that this preliminary assembly of parts may be accomplished, if desired, in separate steps whereby one set of stitches secures the socklining to the upper, while another set of stitches secures the welt strip to the upper.

The line or lines of stitching 13, it will be noted, are spaced appreciably inwardly from the lower edge 14 of the upper. This provides a desirable lasting allowance on the upper.

When the assembled parts are applied to a last, the lasting allowance is pulled into the relationship shown, and adhesively secured to the under surface of the socklining 11. In this way, the upper can be caused to fit neatly and accurately to the contoured surface of the last. An outer sole 15 is then applied to the assembly, with its edge 16 in substantial alignment with the outer edge 17 of the welt strip 12. Suitable adhesive may be used to hold the outer sole in position. Then the structure is removed from the last, and the welt strip is secured to the marginal part of the outer sole by means of stitches 17.

In carrying out this general procedure, it will

be understood that the various layers are brought into closely superposed relationship, with no appreciable gaps between them. The gaps showing in Fig. 2 (and also in Figs. 3 and 4) are the result of the fact that the drawings show the parts in an exaggerated manner, for the sake of clearness. In any case, a layer or layers of filler material such as that shown at 18 in Fig. 2 may be employed wherever their use appears to be expedient. These fillers may be merely layers of cement, or thin pieces of cardboard, or the like.

In the illustrated shoe, which is merely one example of a large variety of footwear items to which the present invention is applicable, the relationship of parts shown in Fig. 2 extends completely around the toe and vamp portions of the shoe, but terminates in the heel region. This is because the shoe chosen for illustration is of the type in which the upper 10 terminates at the rear in a strap-like extension 19 elevated from the level of the heel. In a shoe of this particular kind, the heel 20 may be of any desired kind, and applied in any well-known manner. Usually, the heel seat cover 21 is adhesively applied to its top surface.

It will be understood, however, that the procedure hereinbefore described, and the assembly of parts illustrated in Fig. 2, may apply to all or any desired part of the shoe periphery. For example, in certain types of shoes, the association of the upper with the socklining, welt strip, and outer sole, as shown in Fig. 2, may be used even in the heel region of the shoe.

In Fig. 3 I have illustrated a modification in which the welt strip 22 is carried by the upper 23 through the medium of a platform cover or wrapper 24. In this modified construction and procedure, a socklining 25 is stitched to the upper 23, as before, with its top surface lying next to the inner surface of the upper. By the same line of stitches 26, or by a separate line of stitching, the platform cover 24 is also secured to the upper 23, the outer surface of the cover 24 lying next to the outer surface of the upper 23. Also, as in the procedure hereinbefore described, the line or lines of stitching 26 are spaced appreciably inwardly from the lower edge 27 of the upper, thereby providing a lasting allowance.

Before this assembly is applied to a last, the welt strip 22 is stitched to the free margin of the platform cover 24, by a line of stitching 28.

The structure is then applied to a last, and the upper is fitted to the last by pulling upon the lasting allowance, which brings the parts into the relationship shown. Adhesive means are employed for securing the turned-in margin of the upper to the under surface of the socklining 25. A platform sole or pad 29 is then applied to the last, and preferably held in position by adhesive. The platform cover 24 is then pulled over the margin of the platform sole 29, and held down by adhesive. Then the outer sole 30 is applied, adhesively secured in position, with its peripheral edge 31 in substantial alignment with the outer edge of the welt strip 22. Finally, the parts are removed from the last, and stitching 32 is caused to secure the welt strip 22 to the marginal part of the outer sole 30.

As hereinbefore mentioned, this construction may be coextensive with the entire periphery of the shoe, or with any selected part of it.

In each of Figs. 2 and 3 I have chosen to illustrate a procedure and construction in which the upper consists of a single ply of material. It will be understood that the single plies shown

at 10 and 23 may actually consist of two or more plies adhesively secured together, and treated as a single layer. Under certain circumstances, it is desirable to provide the upper of a two-ply construction in which the plies are secured together only along the top periphery of the upper, thus leaving a space between them. This I have shown in Fig. 4 in which the upper consists of the outer ply 33 and the inner ply or lining 34.

In carrying out the procedure shown in Fig. 4, the parts 33 and 34 are first secured together (as by stitching, not shown) along the top peripheral edge of the upper. The socklining 35 is then stitched, as at 36, to the inner ply 34, with the top surface of the socklining lying against the inner surface of the ply 34. Similarly, a welt strip 37 is secured, as at 38, to the outer ply 33, with the top surface of the welt strip lying against the outer surface of the ply 33. As in the previously-described constructions, the lines of stitching 36 and 38 are spaced appreciably inwardly from the lower edge 39 of the outer ply 33, thus providing a lasting allowance. Although I have shown the outer ply 33 as the one which is provided with the lasting allowance, it will be understood that the inner ply 34 may also have a marginal extension beyond the stitches 36.

The advantage of this construction lies in the fact that the space between the plies 33 and 34 may be utilized to accommodate a suitable reinforcement. For example, a box toe reinforcement 40, such as that shown by itself in Fig. 5, may be fitted into this space. This sandwiching of the reinforcement between the plies 33 and 34 may be accomplished either before or after the assembly is applied to the last. In either case, when the assembly has been lasted, the marginal extension of the outer ply 33 is pulled over the last and adhesively secured in position; or if both the outer and inner plies are provided with lasting allowances, the marginal extension of the inner ply 34 is first pulled over the last and adhesively secured, and subsequently the marginal lasting allowance on the outer ply 33 is pulled over the last and glued down. This fits the upper neatly and accurately to the contoured part of the last.

In Fig. 4, the gap between this turned-in part of the ply 33 and the socklining 35 is quite conspicuous, but, as hereinbefore mentioned, this is merely the result of the exaggerated showing of how the parts are secured to one another. In actual practise, the overlying parts on the top surface of the last are in closely superposed relationship, with or without such filler layers as may be deemed desirable. In fact, in this specification, and in the appended claim, where reference is made to the securing of the lasting allowance to the under surface of the socklining, it is to be understood that the securing may be one which is direct to the socklining, or one which is to a filler, such as that indicated at 18 in Fig. 2.

As one of the concluding steps, the outer sole 41 is adhesively secured to the lasted assembly, 65 with its outer edge 42 in substantial alignment with the free edge of the welt strip 37. Then, when the assembly is removed from the last, a line of stitching 43 is caused to secure the welt strip to the marginal part of the outer sole 41.

By the term outer sole, as used herein and in the appended claim, it will be understood that reference is made to the sole to which a welt strip is finally stitched, in each case.

I have illustratively shown a box toe reinforcement 40 lying between the plies of the upper, in

Fig. 4. The same relationship of parts would exist in the heel region of the shoe, in conjunction with a conventional heel counter, if the procedure and assembly shown in Fig. 4 is resorted to in the heel region of the shoe.

Obviously, the platform sole of Fig. 3 may be employed with a shoe constructed as in Fig. 4, by the simple expedient of attaching the welt strip 31 to a platform cover rather than attaching it directly to the outer ply 33 of the upper, as shown.

The advantages of the present invention will be apparent to those skilled in the art. The simplicity, neatness, comfort, and low expense of the slip lasting procedure are achieved; while at the same time the outer sole is firmly held in position in the advantageous manner afforded by a welt strip. Relatively little skill is required in carrying out the procedure, yet uniformly workmanlike results can be reliably accomplished, with the upper fitting accurately to the last, and with the upper being securely anchored in position as a result of the anchoring extension or lasting allowance which lies in tensioned condition beneath the socklining.

In general, it will be understood that those skilled in the art may readily make changes in the details herein described and illustrated without necessarily departing from the spirit and scope of the invention as expressed in the appended claim.

Having thus described my invention and illustrated its use, what I claim as new and desire to secure by Letters Patent is:

In the making of a shoe, the steps which consist in stitching a socklining and a platform cover to an upper with the top surface of the socklining and the outer surface of the platform cover lying next to the inner and outer surfaces, respectively, of the upper and with the line or lines of stitching spaced appreciably inwardly from the lower

edge of the upper so as to provide a lasting allowance on the upper, stitching a welt strip to the free margin of said platform cover with the top surface of the welt strip lying next to the outer surface of said platform cover, applying said assembly to a last and fitting the upper to the last by pulling upon said lasting allowance and adhesively securing it to the under surface of the socklining, applying to said assembly a platform sole and securing it in position by pulling said platform cover around it and adhesively securing the pulled margin of said platform cover to the under surface of said platform sole, adhesively securing an outer sole to said assembly with the edge of said outer sole in substantial alignment with the outer edge of said welt strip, and stitching said welt strip to the marginal part of said outer sole.

JACK MELTZER.
